Primary Examiner — T. Chase Nelson*Assistant Examiner* — Eric L Goodman(74) *Attorney, Agent, or Firm* — Merchant & Gould P.C.(57) **CLAIM**

The ornamental design for the fluid coupling, as shown and described.

DESCRIPTION

FIG. 1 is a top perspective view of the fluid coupling.

FIG. 2 is a side view thereof; and,

FIG. 3 is an end view thereof.

The broken lines showing aspects of the fluid coupling are for the purpose of illustrating environmental structure and form no part of the claimed design.
